(57) **CLAIM**

The ornamental design for a display screen with an animated graphical user interface, as shown and described.

DESCRIPTION

FIG. 1 is a front view of a first image in a sequence for a display screen with an animated graphical user interface showing the claimed design.

FIG. 2 is a front view of a second image thereof.

FIG. 3 is a front view of a third image in a sequence for a display screen with an animated graphical user interface showing the claimed design.

FIG. 4 is a front view of a fourth image thereof.

FIG. 5 is a front view of a fifth image in a sequence for a display screen with an animated graphical user interface showing the claimed design.

FIG. 6 is a front view of a sixth image thereof; and,

FIG. 7 is a front view of a seventh image in a sequence for a display screen with an animated graphical user interface showing the claimed design.

The outermost broken lines and the broken line showing of rounded shapes illustrate an electronic device and the broken line at the periphery of the animated graphical user interface illustrates the display screen. None of the broken lines form part of the claimed design.
